[57] **CLAIM**

The ornamental design for a sandal, as shown and described.

DESCRIPTION

FIG. 1 is a top plan view of a sandal with the straps omitted for ease of illustration showing my new design; FIG. 2 is a top plan view thereof; FIG. 3 is a top plan view thereof with the straps unbuckled;

FIG. 4 is a bottom plan view of FIG. 2;
FIG. 5 is a bottom plan view of FIG. 1;
FIG. 6 is a right side elevational view of FIG. 1, the left side being a mirror image thereto;
FIG. 7 is a bottom perspective view of FIG. 3;
FIG. 8 is a left front perspective view of FIG. 2;
FIG. 9 is a rear perspective view of FIG. 2;
FIG. 10 is a top and right rear perspective view of FIG. 3;
FIG. 11 is a bottom plan view of FIG. 2 with one side of the strap disconnected for ease of illustration.
